UNITED STATES PATENT OFFICE

KENNETH M. SIMPSON, OF NEW YORK, N. Y.

APPARATUS FOR CARBONIZATION OF COAL

Application filed September 28, 1926. Serial No. 138,287.

The invention relates to improvements in an apparatus for the low temperature carbonization of coals and like materials.

My apparatus broadly consists in providing means for imparting to a series of moving receptacles a carbonizing heat while passing through a heating zone, and in introducing to said receptacles pulverized carbonaceous material while moving through a cooler zone, the heat absorbed by the material constituting the receptacles being sufficient during this latter movement to vaporize out the volatiles from the comminuted carbonaceous material and leave a substantially carbonized product.

In my improved apparatus I preferably utilize a continuous conveyor consisting of interconnected receptacles adapted to pass through a heating zone to receive their carbonizing heat after which material is introduced to said vessels while moving through a cooler zone, the heat absorbed by the material constituting the vessels, being, however, sufficient to carbonize the introduced charge of finely comminuted material. It is therefore apparent that no direct heat is applied to the vessels while filled with carbonaceous materials and that the low temperature carbonization occurs solely by reason of the heat contained in the vessels.

In the accompanying drawings I have shown the preferred embodiment of an apparatus capable of supporting this process, in which Figure 1 represents a vertical longitudinal cross sectional view of my apparatus; and,

Figure 2 is a cross-sectional view through the apparatus.

Referring now more particularly to the drawings wherein like reference characters indicate corresponding parts, the numeral 1 designates a furnace structure which may be formed of any desired and conventional material and which is provided with an open interior 2 adapted to receive the interposed hearth 3 constructed of brick or the like. The bottom 4 of the furnace is formed with flues 5, these flues being adapted to conduct heating gases into the open interior 2 of the furnace from the combustion chamber 5'

seated beneath this wall. Gases or the like, are burned in the combustion chamber by means of the burner 6 to supply the necessary heat for carrying out the process.

The furnace is provided with a top wall 55 having a vapor outlet 7 leading therefrom, which extends to any suitable receiver, condenser or the like.

Disposed within the interior 2 of the furnace 1 near each side of the hearth 3 I provide 60 sprockets 7' and 8 around which an endless conveyor 9 passes, the conveyor 9 consisting of a series of metallic pans 10 carried by sprocket chains 11 extending around the sprockets 7' and 8. These pans 10 substantially abut one another and offer a continuous conveying surface. The sprockets 7' and 8 are driven by hand or any suitable power mechanism.

It will be apparent that the flues 5 heat the under side of the retort opening 2 so that the metallic pans 10 receive their maximum heat while travelling on the under side of the hearth 3 and adjacent the flues 5. The retort near its forward end is provided with an outlet opening 13 which is sealed to prevent the discharge of heat from the chamber 2 and through which opening carbonized particles, coal and the like are discharged from the pans 10, as they move around the sprockets 7'. 70

Adjacent the main conveyor 9 I provide an auxiliary conveyor 14, the same consisting of a series of pans similar to the pans 10 connected together by chains travelling around the sprockets 15 and 16. The auxiliary conveyor 14 feeds to the main conveyor 9, if this is found to be desirable, or the main conveyor can be fed entirely independently of the auxiliary conveyor. To this end I provide a feed 16' for the auxiliary conveyor and a feed 17 for the main conveyor. Pulverized materials, such as powdered coal, mixtures of coal and oil, and the like fill the feed hoppers 16' and 17 and regulated quantities of this material can be dropped into the pans carried by the conveyor chains from time to time during the operation of the apparatus. It will be observed that the pans 10 are constructed of cast iron or similar metal which will absorb and retain sufficient quantities of heat when 75

passing beneath the flues 5 to cause a low temperature carbonization of the material later introduced to said heated pans when travelling over the hearth 3. It may be necessary at times to construct the pans of unusual thickness in order that they will retain sufficient heat to cause the carbonization. It is one of the salient objects of this invention to also provide an improved process for the low temperature carbonization of fuels which may be carried out in an apparatus of the character herein disclosed.

The process briefly consists in subjecting a plurality of pans, vessels or the like to a temperature while they contain no coal or other carbonaceous fuels, and after said pans have been highly heated and while moving through a cooler zone I then introduce to the pans charges of finely pulverized carbonaceous materials. The temperature of the pans is sufficient after the introduction of such materials thereto to vaporize out the volatiles contained in the fine coal particles leaving a substantially carbonized residue.

In the process it is necessary that the pans possess a sufficient quantity of metal or other material which will absorb and retain the desired amount of heat to effect the carbonization of the coal. I have found, however, that pans constructed of relatively thick cast iron material will very satisfactorily perform this process.

In carrying out the process in the apparatus herein described, I heat the retort to a temperature well in excess of 700° C., the temperature being sufficient, however, to heat the cast iron pans 10 to a temperature of at least 700° C.

In each pan I deposit pulverized coal in a layer of say one-half inch thickness, which coal may be deposited directly to the pans 10 through the main feed 17 or may be reheated before it enters the pans in the main conveyor by first having travelled the length of the auxiliary conveyor 14 from where it is discharged into the pans of the main conveyor 9. In other words, the supplemental feed may be used if desirable, but it need not be used if satisfactory conditions can be obtained by depositing the material from the feed 17 directly into the pans of the main conveyor. The pans travel very slowly through the main conveyor, and in fact just as soon as each pan passes around the sprocket 8 it receives its fuel charge and it may require approximately fifteen minutes to move this charge to the outlet 13 at the opposite side of the retort. The hearth 3 is maintained at a comparatively high temperature so as to prevent a sudden cooling of the pans when moving above said hearth. In fact, when the pans are at a temperature of say 700° C. when they move around the sprocket 8 said pans may be of a temperature of approximately 500° C. when passing around the sprocket 7.

It will be apparent that during this heat treatment volatiles are being driven from the coal charge, and these volatiles pass out through the vapor discharge pipe 7. The carbonized residue from each pan is automatically discharged into the opening 13 as the pans pass around the sprocket 7.

It will be clearly apparent that it is vital in this process that the cast iron pans should be of sufficient size to absorb that amount of heat necessary to distill the volatiles from the coal charges and to convert the residue into coke. The coal will ordinarily have to be subjected to a temperature of not less than 500° C. to properly cause its distillation and in carrying out this process I therefore utilize pans of sufficient thickness to retain this temperature when the pans are travelling over the hearth 3. By this process the maximum temperature is not applied directly to the pans while they contain the coal undergoing treatment, but the heat absorbed in the pans during their heat treatment while free of coal is utilized for the low temperature distillation of the coal subsequently applied to the heated pans.

In the accompanying claims I have referred to the apparatus as embodying a heating compartment, and a distilling compartment. By the heating compartment I mean the compartment A between the heating flues and the brick hearth 3, while by the term distilling compartment I have in mind the compartment B overlying the hearth 3, or that space between the upper surface of the hearth and the top of the retort.

This application is a continuation in part of my prior application, Serial No. 723,022, filed June 28, 1924.

Having thus described my invention, what I claim is:

1. An apparatus for carbonizing coal comprising a horizontally disposed retort, a horizontal baffle member within said retort dividing the same into a lower heating compartment and an upper distilling compartment having an inlet end and an outlet end, a combustion chamber, means for passing hot combustion gases from said chamber into said heating and distilling compartments, an endless carrier formed of a material capable of absorbing a carbonizing heat disposed within said retort and positioned for movement around said baffle member, means for moving said carrier through said heating compartment and then through said distilling compartment from said inlet end thereof to said outlet end thereof, means at said inlet end of the distilling compartment for charging coal onto said carrier, and means at said outlet end of the distilling compartment for discharging the coal from said carrier.

2. An apparatus for carbonizing coal comprising a horizontally arranged retort having an end wall, a horizontal baffle member with-

in said retort terminating short of said end wall and dividing said retort into a lower heating compartment and an upper distilling compartment having an inlet end adjacent 5 said wall and an oppositely disposed outlet end, an endless carrier formed of a material capable of absorbing a carbonizing heat disposed within said retort and positioned for movement around said baffle member, means for moving said carrier through said heating compartment and then through said distilling compartment from said inlet end thereof to said outlet end thereof, a combustion chamber, means for passing hot 10 combustion gases from said chamber into said heating and distilling compartments, means within said retort adjacent said end wall and said inlet end of the distilling compartment for receiving and delivering coal 15 to said carrier, and means at said outlet end of said distilling compartment for discharging the coal from said carrier.

20

3. An apparatus for carbonizing coal comprising a horizontally arranged retort having an end wall, a horizontal baffle member within said retort terminating short of said end wall and dividing said retort into a lower heating compartment and an upper distilling compartment having an inlet end 25 adjacent said wall and an oppositely disposed outlet end, an endless carrier formed of a material capable of absorbing a carbonizing heat disposed within said retort and positioned for movement around said baffle member, means for moving said carrier through said heating compartment and then through said distilling compartment from said inlet end thereof to said outlet end thereof, a combustion chamber, means 30 for passing hot combustion gases from said chamber into said heating and distilling compartments, an endless conveyor within said retort adjacent said end wall and said inlet end of the distilling compartment and 35 arranged for discharge onto said carrier at said inlet end of the distilling compartment, means for feeding coal to said conveyor, and means at said outlet end of said distilling compartment for discharging the coal from 40 said carrier.
